SCATTER-SHOT ARROW

James C. Ramsey, Lincoln, N. Mex.

Application April 14, 1958, Serial No. 728,247

9 Claims. (Cl. 273—106.5)

The present invention relates to scatter-shot arrows, and more particularly to a device for projecting a plurality of arrow members with a single bow shot.

The primary object of the invention is to provide an arrow of the class described above having a plurality of missile arrows mounted thereon and projected thereby when fired with a bow.

Another object of the invention is to provide a scatter-shot arrow of the class described above having positive means for releasing the arrow missiles when desired.

A further object of the invention is to provide a scatter-shot arrow of the class described above wherein the main arrow is provided with a pointed head for target penetration in addition to supporting and projecting a plurality of missile arrows.

A still further object of the invention is to provide a scatter-shot arrow of the class described above which is inexpensive to manufacture, simple to use, and which is completely positive in the launching of the missile arrows therefrom.

Other objects and advantages will become apparent in the following specification when considered in the light of the attached drawings, in which:

Figure 1 is a side elevation of the invention shown partially broken away for convenience of illustration, with the missile arrows shown mounted thereon prior to launching.

Figure 2 is a fragmentary side elevation of the invention illustrating the missile arrows in launched position immediately after the firing of the arrow.

Figure 3 is a perspective view of one of the missile arrows.

Figure 4 is an enlarged transverse cross-section taken along the line 4—4 of Figure 1, looking in the direction of the arrows.

Figure 5 is an enlarged transverse cross-section taken along the line 5—5 of Figure 1, looking in the direction of the arrows.

Figure 6 is an enlarged transverse cross-section taken along the line 6—6 of Figure 1, looking in the direction of the arrows.

Figure 7 is an enlarged transverse cross-section taken along the line 7—7 of Figure 1, looking in the direction of the arrows.

Figure 8 is a fragmentary longitudinal cross-section taken along the line 8—8 of Figure 6, looking in the direction of the arrows.

Figure 9 is a perspective view of the missile arrow clamp shown removed from the scatter-shot arrow.

Figure 10 is a perspective view of a modified form of missile arrow clamp.

Figure 11 is a fragmentary side elevation of a modified form of clamp pull pin tether structure.

Figure 12 is a side elevation of a modified missile arrow.

Figure 13 is a side elevation of another modified missile arrow.

2

Referring now to the drawings in detail wherein like reference characters indicate like parts throughout the several figures, the reference numeral 20 indicates generally a scatter-shot arrow constructed in accordance with the invention.

The scatter-shot arrow 20 comprises an elongated arrow shaft 21 provided with fletching 22 at its rear end. A missile head, generally indicated at 23, comprises a center rod 24 arranged in axially aligned relation to the forward end of the arrow shaft 21. An integral enlarged socket forming portion 25 is formed on the rear end of the center rod 24 and telescopically engaged over the front end of the arrow shaft 21.

The center rod 24 terminates in an arrow point 26. A generally circular fore end rest 27 is provided with a forward tapering portion 27a and is slidably on and frictionally secured to the center rod 24. The fore end rest 27 is provided with a plurality of longitudinally extending peripheral notches 28. A generally circular middle rest 29 is arranged in parallel relation to the fore rest 27 and slidably mounted on the center rod 24 at a rearwardly spaced point from the fore rest 27. The middle rest 29 is provided with a plurality of longitudinally extending peripheral notches 30 in aligned relation to the notches 28 on the fore rest 27. The middle rest 29 may in some cases be omitted entirely.

A generally circular rear rest 31 is mounted on the socket forming portion 25 in parallel relation to the middle rest 29 and is provided with a plurality of longitudinally extending peripheral notches 32 aligned with the notches 30 and the notches 28 in the middle rest 29 and fore rest 27 respectively.

A pusher plate 33 having a diameter somewhat greater than the rear end rest 31 is positioned immediately rearwardly of the rear end rest 31 and secured thereto. The pusher plate 33 is provided with a plurality of longitudinally extending sockets 34 arranged in aligned relation with the peripheral notches 32 in the rear end rest 31.

A plurality of missile arrows 35 have a shaft 36 having fletching 37 at one end thereof and an arrow point 38 at the opposite end. Each missile arrow 35 is supported in the notches 28, 30, 32 of the fore rest 27, middle rest 29, and rear end rest 31, respectively, with the rear end 39 of the missile arrow supported in the socket 34 in the pusher plate 33.

The forward ends of the missile arrows 35 are secured in the notches 28 of the fore end rest 27 by means of an elastic loop 40 extending thereabout. A U-shaped connecting link 41 is secured to one end of the loop 40 and a tongue connecting link 42 is secured to the opposite end, as best seen in Figure 9, and the tongue 42 is detachably secured to the U-shaped link 41 by a pull pin 43 extending therethrough.

A tether 44 is connected to the pull pin 43 and extends rearwardly therefrom. The tether 44 is secured to a concave disk 45 having a hub 46 engaged over the rear end of the arrow shaft 21.

In the use and operation of the invention, the arrow 20 is shot from a bow in the normal manner and the action of the wind on the concave disk 45 causes the disk 45 to pull on the tether 44 removing the pull pin 43 from the connecting links 41, 42 so that the elastic band 40 is released from encompassing relation to the missile arrows 35.

The push plate 33 is pushing the missile arrows 35 forwardly, and since the resistance to the passage of the arrow 20 is greater than that for the passage of the missile arrows 35, the missile arrows 35 move ahead of the arrow 20 in a scatter-shot pattern effective to cover a target of a wide area.

In Figure 10 a modified form of the invention is illustrated wherein the pull pin 43 directly connects the oppo-

site ends of the elastic loop 40a eliminating the necessity of additional couplings.

In Figure 11 another modified form of the invention is illustrated wherein the tether 44a has the rear end thereof connected to the bow string 47 so that the pull pin 43 is withdrawn from the loop 40 as soon as the arrow 20 leaves the bow.

A modified missile arrow 35a is illustrated in Figure 12. The missile arrow 35a has an elongated shank 36a sharpened at 38a to form a point and terminating at 39a 10 in a blunt rear end.

A further modified missile arrow 35b is illustrated in Figure 13. The missile arrow 35b has an elongated shank 36b sharpened at 38b to form a point and provided with fletching 37b adjacent the rear end 39b thereof.

The position of the fore rest 27 can be used to adjust the flight pattern of the missile arrows 35 by using a fore rest 27 having a lesser or greater diameter than the rear rest 31. In such cases the fore rest 27 can be axially moved with respect to the rear rest 31 to vary the angular relation between the missile arrows 35.

Having thus described the preferred embodiments of the invention, it should be understood that numerous structural modifications and adaptations, in addition to those shown, may be resorted to without departing from the scope of the appended claims.

What is claimed is:

1. A scatter-shot arrow comprising an elongated arrow shaft, a rod telescoped over the forward end of said arrow shaft and extending forwardly therefrom, a plurality of circular rests slideable on and frictionally secured to said rod in spaced apart relation, said rests each having a plurality of longitudinally extending peripheral notches formed therein, a pusher plate positioned adjacent the rear end of said rod, a plurality of missile arrows supported on said circular rests in the notches therein with their rear ends in engagement with said pusher plate, and releasable means clamping said missile arrows to said rests.

2. A device as claimed in claim 1 wherein means are 40 provided for releasing said releasable means upon forward movement of said arrow.

3. A device as claimed in claim 1 wherein said releasable means comprises an elastic loop encompassing said missile arrows, a pull pin securing said elastic loop in 45 clamping position, and a tether having its forward end secured to said pull pin and its rear end secured to means for restraining forward movement of said tether on forward movement of said arrow.

4. A device as claimed in claim 3 wherein said means to which the rear end of said tether is attached comprises a disk supported on the rear end of said arrow shaft and arranged for sliding removal therefrom on said motion of said arrow.

5. A device as claimed in claim 1 wherein said pusher plate is provided with a plurality of missile arrow rear end receiving sockets, and said missile arrows are secured to the foremost circular rest adjacent the front end of said arrows.

6. A device as claimed in claim 1 wherein said rod is provided with an arrow head at the end thereof opposite said arrow shaft.

15 7. A device as claimed in claim 3 wherein the rear end of said tether is adapted to be secured to the bow string of the bow used to project said arrow.

20 8. A scatter-shot arrow comprising an elongated arrow shaft, a rod telescoped over the forward end of said arrow shaft and extending forwardly therefrom, a plurality of circular rests secured to said rod in spaced apart relation, said rests each having a plurality of longitudinally extending peripheral notches formed therein, a pusher plate positioned adjacent the rear end of said rod, a plurality of missile arrows supported on said circular rests in the notches therein with their rear ends in engagement with said pusher plate, and releasable means clamping said missile arrows to said rests.

25 9. A scatter-shot arrow comprising an elongated arrow shaft, a rod telescoped over the forward end of said arrow shaft and extending forwardly therefrom, a plurality of circular rests fixedly secured to said rod in spaced apart relation, said rests each having a plurality of longitudinally extending peripheral notches formed therein, a pusher plate positioned adjacent the rear end of said rod, a plurality of missile arrows supported on said circular rests in the notches therein with their rear ends in engagement with said pusher plate, and releasable means clamping said missile arrows to said rests.
